CLAIM

The ornamental design for a windshield wiper, as shown and described.

DESCRIPTION

FIG. 1 is a top perspective view of the windshield wiper of the present invention;

FIG. 2 is a top view thereof;

FIG. 3 is a bottom view thereof;

FIG. 4 is a bottom perspective view thereof;

FIG. 5 is end view thereof;

FIG. 6 is a view of the opposite end thereof;

FIG. 7 is a left side view thereof; and,

FIG. 8 is a right side view thereof.

The broken lines in the drawings are included for the purposes of illustrating portions of the wiper blade which form no part of the claimed invention.
